TREATMENT OF PATHOLOGICAL
AFFECTIONS

Ralph E. Hall, Mount Lebanon, Pa., assignor to
Hall Laboratories, Inc., Pittsburgh, Pa., a cor-
poration of Pennsylvania

No Drawing. Application August 18, 1933,
Serial No. 685,750

5 Claims. (Cl. 167—72)

The present invention relates to the treatment of pathological affections, and more especially to the treatment of such affections as sunburn, burns and scalds, ivy poisoning, eczema, dandruff, mange, and the like.

According to my invention, such pathological skin affections are treated by thoroughly bathing or scrubbing them with a weak solution of an alkali-metal metaphosphate, preferably sodium metaphosphate. I preferably use about a 1% solution by weight of the variety of sodium metaphosphate known as "Graham's salt" (Text-book of Inorganic Chemistry, edited by J. Newton Friend, vol. 6, part 1, page 177, by J. B. R. Prideaux, Philadelphia, 1934; Gmelin, Handbuch der Anorganischen Chemie, vol. 21, page 922, 8th edition, Berlin, 1928); or "Graham's metaphosphate" (A Dictionary of Chemistry, by Henry Watts, vol. 4, page 578, New York, 1873; A Treatise on Chemistry, by Roscoe & Schorlemmer, vol. 2, part 1, page 283, New York, 1923). Graham's salt may be produced by strongly heating monosodium dihydrogen orthophosphate (NaH_2PO_4) until water is given off and the orthophosphate is converted into the sodium metaphosphate NaPO_3 . The heating is carried out until the mass becomes fused, after which it is quickly cooled as by pouring it in thin layers over cold metal surfaces, resulting in a solid material of an amorphous glass-like appearance. This material is readily soluble in water. The sodium metaphosphate gives a somewhat acid solution of a pH value of about 6. For the application to the skin the pH value of the solution is preferably adjusted for slight alkalinity by the addition of sodium carbonate or sodium bicarbonate with a small amount of sodium bicarbonate, or by the addition of sodium pyrophosphate or other alkaline buffering salt. The solution is preferably adjusted to have a pH value of about 8 to 8.5, which is mildly alkaline.

In the treatment of sunburn, for example, the sunburned skin is thoroughly washed with this solution. Actual treatments have shown that the pain is almost instantly alleviated, the redness reduced, and the blistering and peeling prevented. The treatment has a similar effect upon ordinary burns and scalds.

In the treatment of ivy poisoning, the poisoned skin areas are likewise washed with this solution. Actual treatments have shown that the intense itching is quickly reduced and the irritation alleviated.

55 Cases of eczema have yielded to this treatment

and in a number of instances the eczema condition has entirely disappeared.

In the treatment of dandruff, the scalp should be washed regularly, say, every few days, with the solution of sodium metaphosphate, preferably 5 as a rinse for the hair after bathing. The metaphosphate solution not only thoroughly removes the scurf skin characteristic of dandruff, but effectively prevents the continuance of the dandruff condition.

The treatment is also efficacious in alleviating skin affections of animals, such, for example, as mange in dogs. Tests have shown a number of instances where mange has completely disappeared after several washings with the sodium 15 metaphosphate solution.

While at the present time the treatment with the metaphosphate solution has been carried out for the pathological skin affections mentioned above, the treatment is applicable to other pathological skin affections, particularly skin irritations where toxic poisoning is introduced into the skin, or where the skin is clogged with waste 20 products.

The exact biochemical phenomena which underlie the effects noted are at present unknown to me, but a large number of actual trials have demonstrated the beneficial effect in the alleviation and cure of the above-mentioned pathological skin affections. Some of the pathological 25 skin affections, such as ivy poisoning and some forms of eczema, are probably caused by outside poisonous bodies introduced into the skin. The pain and redness from sunburn and other burns and scalds is apparently caused by the production within the skin itself of certain toxins due to the breaking down of some of the skin tissue. In the case of dandruff the skin is probably 30 clogged with waste matter.

As a possible explanation, I may state that the 40 sodium-metaphosphate molecule is a chemically active molecule. The molecular formula is probably $\text{Na}_2(\text{Na}_4\text{P}_6\text{O}_{18})$. This molecule combines with calcium and many of the other metals to form a molecule probably having the composition 45 $\text{Na}_2(\text{X}_n\text{P}_6\text{O}_{18})$, in which the metal X is in an extremely slightly ionizable condition. The effect of the sodium metaphosphate is therefore to very actively combine with certain substances, such as calcium, and sequester them in a complex molecule and in an exceedingly slightly ionized condition. The complex molecule, however, is soluble. The effect of washing with the sodium metaphosphate solution in the case of dandruff treatment, particularly after washing the hair in the usual 50 55

way, is, among other things, to thoroughly cleanse the scalp from the lime and magnesium soaps resulting from ordinary hair washing and which would otherwise tend to clog the scalp. It is 5 probable that the sodium-metaphosphate molecule has a similar effect in combining with and rendering inert the irritating toxins which are present in ivy poisoning, eczema, burns, etc. At any rate, its action appears to be the rendering 10 inert or possible removal of the irritating poisons which cause the redness and pain in sunburn and other burns and ivy poisoning.

I have also found that the sodium metaphosphate has a strong detergent effect, particularly 15 upon the waxes and greases, in a neutral or but slightly alkaline solution, as contrasted with the detergent effects secured by the use of harsh alkalies. I believe that the sodium metaphosphate removes from the skin the waste sebaceous 20 material, and other things which may clog the pores, and possibly may remove from the skin the toxins as well.

While I prefer to use the slightly alkaline solution of Graham's salts, solutions of other water 25 soluble alkali-metal metaphosphates may be used, such as those of the other alkali-metals, potassium, lithium, etc.

The term "aqueous solution" in the claims

means a solution containing water and is not necessarily limited to a solution containing only water and the solute.

While I have specifically described my invention with particular reference to the best procedures now known to me, it is to be understood that the invention is not so limited but may be otherwise embodied and practiced within the scope of the following claims.

I claim:

1. As a remedy for treating pathological skin affections, a weak aqueous solution of an alkali-metal metaphosphate. 10
2. As a remedy for treating pathological skin affections, a weak aqueous slightly alkaline solution of an alkali-metal metaphosphate. 15
3. A remedy for treating pathological skin affections, containing a weak aqueous solution of an alkali-metal metaphosphate as an essential ingredient. 20
4. As a remedy for treating pathological skin affections, a weak aqueous solution of Graham's salt. 25
5. As a remedy for treating pathological skin affections, a weak aqueous slightly alkaline solution of Graham's salt.

RALPH E. HALL.
